UNITED STATES PATENT OFFICE.

ARTHUR B. BELLOW, OF PITTSBURG, PENNSYLVANIA.

CAR TRUCK AND BOLSTER.

SPECIFICATION forming part of Letters Patent No. 726,500, dated April 21, 1903.

Application filed April 19, 1902. Serial No. 103,750. (No model.)

To all whom it may concern:

Be it known that I, ARTHUR B. BELLOW, of Pittsburgh, in the county of Allegheny and State of Pennsylvania, have invented a new 5 and useful Car Truck and Bolster, of which the following is a full, clear, and exact description, reference being had to the accompanying drawings, forming part of this specification, in which—

10 Figure 1 is a top plan view of my improved truck-bolster in position. Fig. 2 is a front elevation of the same, partly in section. Fig. 3 is an end elevation of the truck with the bolster in place. Fig. 4 is a cross-section of the transom of Fig. 1; and Figs. 5, 6, 7, and 8 are views similar to Figs. 1, 2, 3, and 4, respectively, showing a modified form of the invention.

15 My invention relates to the trucks and truck-bolsters employed in railway-cars, and is designed to decrease the weight of the bolster and truck, to arrange the bolster so that all its supporting-springs will be under compression at all times, to provide improved 20 side bearings, and to improve the general construction of the truck.

25 Referring to the form of Figs. 1, 2, 3, and 4, 2 represents the upper arch member, 3 the inverted arch member, and 4 the tie-bar, of an ordinary diamond truck. The transom is shown as formed of two parallel channels 5 with outwardly-directed flanges, and at the ends of the transom are secured upper and lower U-shaped plates 6, the bases of which are riveted to one of the arch-bars, while the flanges are riveted to the webs of the channels. 30 The bolster, which in this form is shown as composed of two I-beams 7, with top and bottom connecting-plates 8 riveted to their flanges, is located at the central portion of transom and is shorter than the transom member, its ends terminating within the side bearings. The ends of the bolster are guided by angles 9, riveted to the inner faces of the 35 transom-channel. The bolster rests upon springs 10, of which I have shown eight, in two sets of four each. Each set rests at the bottom upon a wooden filler-block 11 within an open-top box 12, preferably formed of a 40 pressed-steel plate with a flange extending around it. The side portions of the flanges are riveted through reinforcing angle-plates

13 to the channel-webs, and a strengthening-plate 14 extends across the base of the transom at its intermediate part and is riveted to 45 the bottom channel-flanges.

50 The center plate 15 is riveted to the upper plate 8 of the bolster. Straps 16 extend across the ends of the bolster and are bolted to the upper channel-flanges, these straps serving 55 as stops to limit the upward movement of the bolster.

55 As the bolster is located at the center of the transom and extends only through its intermediate part, I provide yielding side bearings. I have shown these bearings as consisting of a lower pressed-up box 17, with its end flanges riveted to the channel-webs. This box contains a wooden filler-block 18, upon which rest the springs 19. These springs 60 at their upper end bear against the inner face of a pressed-steel member 20 of inverted-U shape, whose depending side flanges 21 inclose the side flanges of the box 17 to guide the vertical movements. A casting 22 is fastened 65 to the top of the member 20 and contains a ball-bearing 23.

70 In the use of the bolster the weight of the car is carried upon the springs 10, and when the car-body tilts the bolster will tilt slightly; 75 but all of its supporting-springs will still remain under compression. Under this condition one of the side bearings will be depressed against the yielding spring-pressure. On level portions of the track the springs which 80 support the bolster will be under substantially equal pressure, and in its vertical 85 movements it is guided by the brackets or angles 9.

90 In the form of Figs. 5 to 8, inclusive, I show a construction in many features similar to that of the form of Figs. 1 to 4, similar parts being designated by similar numerals with the prime-mark. In this form, however, the bolster is made shallower by doing away with 95 the I-beam portion of the body-bolster and providing an inverted-box structure 24, which forms the bolster-body. This box is preferably formed of a pressed shape or shapes with end flanges 25 and side flanges 26. The center plate 15' is secured to the central portion of the box. In this case I have shown the spring-supports 12' as at an intermediate 100 level in the height of the bolster, while the

lower flanges of the channels are connected by the plate 14'. The action of this form is substantially the same as that in the first form.

5 The advantages of my invention result from the considerable decrease in weight, owing to the short bolster, also from the constant compression of all the bolster-springs in any position of the car-body, and, further, from the 10 yielding side bearings and simple and strong construction of the transom and bolster.

The bolster and side bearings may be applied to the car instead of the truck, and many other variations may be made in the form and

15 arrangement of the truck, the transom, the bolster, side bearings, &c., without departing from my invention.

I claim—

1. A truck having a transom formed of laterally-separated members, a short stiff bolster located between said members and terminating between the side bearings, spring-supports secured rigidly between the transom side members, and springs thereon located 25 beneath and supporting the short bolster; substantially as described.

2. A truck having a transom formed of laterally-separated side members, yielding side bearings, a short stiff bolster located between 30 the side members, spring-bearings secured rigidly beneath the bolster and between the side members, and springs thereon supporting the bolster; substantially as described.

3. A truck having a transom with separated 35 side members, a stiff bolster between the side members and terminating between the side bearings, end guides for the bolster secured to the inner faces of the side members, and bolster-supporting springs carried on supports secured to the side member; substantially as described.

4. A transom having separated side members, a stiff bolster shorter than the transom

and located between its side members, a center plate carried on the bolster, spring-supports beneath the bolster and secured rigidly between the side members, and springs thereon supporting the stiff-bolster member; substantially as described.

5. A transom having intermediate flanged 50 supports secured rigidly between its separated side members, springs resting on said supports, a short stiff bolster resting on the springs, and end guides for the bolster, all said parts being located in the intermediate 55 part of said transom and between its side members; substantially as described.

6. A transom having a strengthening-plate secured across the base portions of the separated transom members at their central portion, and bolster-springs carried on a rigid support secured above said plate and between the separated transom members; substantially as described.

7. A car-truck having spring-supported side 65 bearings, guides therefor, a short central bolster with its ends between the side bearings, and spring-supports for the bolster secured rigidly to the transom said parts being placed between the separated webs of the side members of the transom; substantially as described.

8. A transom having separated flanged side members the flanges being reinforced; substantially as described.

9. A transom having separated flanged side members the flanges being reinforced by added flanged members, and a bolster between said side members; substantially as described.

In testimony whereof I have hereunto set my hand.

ARTHUR B. BELLows.
